TOOTH PASTE TUBE CLOSURE

Charles Johnson and Carl B. Johnson,
Salt Lake City, Utah

Application February 27, 1939, Serial No. 258,602

3 Claims. (Cl. 221—60)

Our invention relates to collapsible tube and paste caps and like articles for closing the opening of collapsible tubes in which tooth paste, shaving soap, or creams are packed and which cap is quickly and efficiently opened and closed. A further object is to provide a hinged cap for collapsible tubes which will be spring controlled and which is manually opened, locked open by a spring catch and automatically closed by spring tension the moment that the catch is released.

A still further object is to provide a simple, economical, and efficient cap for collapsible tubes which will be manually operated to open it, but which will then remain open until the cap is pressed or the catch released.

These objects we accomplish with the device illustrated in the accompanying drawing in which similar numerals and letters of reference indicate like parts throughout the several views and as described in the specification forming a part of this application and pointed out in the appended claims.

In the drawing,

Figure 1 is a side elevation of a collapsible tube with my cap shown thereon in closed position.

Figure 2 is a like view with the cap shown open and some of the paste being pressed from the tube.

Figure 3 is a diametrical longitudinal section of the cap removed from a tube shown in increased size for clarity.

Figure 4 is a plan view of the cap shown closed.

In the drawing we have shown the collapsible tube as A, and with the threaded discharge neck shown as 5. Onto this neck we screw our cap assembly B. This assembly is made with a hexagonal internally threaded base 7 terminating in a cylindrical discharge nozzle 8 and on one side of this cylindrical nozzle 8 we provide spaced apart brackets 9 to which the hinge ears 10 of the closure plate or cap 11 of our device are hingedly mounted by a hinge pin 12. A closure spring 13 is wound around the hinge pin 12 with one end engaging the cap and the other end resting against the side of the nozzle 8; the tension of the spring being such that it will normally tend to insure close inter-engagement between cap 11 and the open end of nozzle 8. The cap 11 is provided with an annular flange therearound to hold a packing or gasket 14 in place, said packing or gasket being of cork, foil, or other suitable sealing material, such as is normally used.

The spring held catch for the cap is formed of a coil spring 15 mounted on the cylindrical nozzle 8 by brackets 16, the end 17 of the spring 15 being bent up parallel to the axis of the nozzle 8 with a slight curve 18 formed in the end 17 to engage the top of the cap 11 when it is opened.

A release bar 19 is mounted on the free end of the spring 15 by which the spring may be flexed to release the cap after it has been opened and locked open by the spring.

The spring is the retaining means for holding the cap open and when the user has opened the cap the curved portion 18 of the spring engages over the small lug, shown on the drawing in the adjacent end of the cap, holding the cap in the opened position, as shown in Figure 2 of the drawing. The cap is released by touching the release bar 19 either with the finger or any other object.

Having thus described our invention we desire to secure by Letters Patent and claim:

1. A closure for collapsible tubes comprising, an internally threaded base adapted to be screwed into the discharge neck of a collapsible tube; a smaller diameter discharge nozzle on said base; a bracket formed on one side of said smaller nozzle; a cap having the main body formed circular to fit over the end of the discharge nozzle of said base and with one side extended and formed with ears depending from said extended side, said ears being pivoted to said bracket; a spring between the discharge nozzle and the cap to normally hold the cap in closed position; and a latch spring mounted on the back of the base adapted to engage the top side of the extended side of the cap when it is opened and hold it open until released by releasing said spring.

2. A closure for collapsible tubes comprising a threaded tubular body adapted to screw onto the discharge neck of a collapsible tube; a cap pivotally mounted on said threaded body normally closing the end of said tubular body; a spring normally holding the cap in the closed position; and an extended spring having one portion adapted to engage the cap when opened and hold it open until released.

3. A closure of the class described in claim 2 including a packing within an annular flange on said cap to prevent leakage from said cap when closed.

CHARLES JOHNSON.
CARL B. JOHNSON.
